CONTROL SYSTEM FOR HYDRAULIC PRESSES

Walter Becker, Dayton, Ohio, assignor to The Hydraulic Development Corporation, Inc., Wilmington, Del., a corporation of Delaware

Application November 19, 1943, Serial No. 510,891

14 Claims. (Cl. 60—52)

1

This invention relates to control systems, and, in particular, to control systems for hydraulic circuits.

It is well known that, when a hydraulic press having a vertically reciprocable ram stands idle for a relatively long period of time with the pump units idle, the press ram gradually settles downwardly due to leakage around the driving motor or press piston. Then, when it is desired to put the press in operation, it is necessary first to return the ram to its full retracted or starting position.

It is customary to interconnect the press platen or ram by means of linkage with a fluid flow varying device, such as the flow control member of a variable delivery pump, whereby the flow of fluid to the retracting means of the hydraulic motor is neutralized at the end of the retraction stroke of the press. In this manner the press ram automatically comes to a halt at the end of the retraction stroke. Therefore, when the press ram settles or slides downwardly as has been previously explained, the flow controlling means operated by the linkage interconnected with the platen is shifted to direct fluid to the retraction area of the press. If the fluid is supplied by, say, a variable delivery pump, the pump will start under load due to the settling of the ram. In turn, the prime mover for driving the pump will also be started under load and, in the case of an electric motor as the prime mover, expensive and complicated starting devices are required in order not to overload the power lines supplying energy to the driving motor.

Accordingly, it is an object of this invention to provide means whereby the prime mover driving the pump may be started under no load conditions, regardless of the position occupied by the press ram.

In the operation of the press it is often desirable suddenly to halt the press in order to prevent possible damage to the work piece being operated, the dies or other tools mounted in the press, the press itself, or to prevent injury to an operator.

It is, therefore, an object of this invention to provide a control system for a hydraulic circuit which is adapted suddenly to cause a cessation in the flow of pressure fluid in the system.

This application is a continuation-in-part of my copending application Serial No. 470,268, filed December 26, 1942.

These and other objects and advantages of this invention will be more clearly apparent from the

5 following specification in connection with the drawings wherein:

Figure 1 diagrammatically illustrates one embodiment of the control system according to this invention in connection with a hydraulic press circuit, and

Figure 2 is a wiring diagram used in connection with the control system of Figure 1.

General arrangement

10 The control system according to this invention comprises a variable delivery pump including centering springs continuously urging said pump into neutral or no delivery position, while servomotor means is connected with the pump for selectively shifting the pump into forward or retraction stroke delivery position.

15 The servomotor means, which may be of any standard type, preferably fluid operable, includes a valve member and a reciprocable plunger operable by pressure fluid from an auxiliary fluid source, the hydraulic connection of which with said servomotor means is controlled by valve means or similar fluid flow controlling devices.

20 The pump is connected with a prime mover in such a manner that when the prime mover is started the pump is also started, while the valve means previously referred to as controlling the flow of pilot fluid to the servomotor is actuated so as to prevent the delivery of pilot fluid to the servomotor until the prime mover reaches a predetermined speed. When this speed has been reached, or after a predetermined time period has elapsed following the initiation of the starting of the prime mover, the valve means controlling the fluid connection between the auxiliary fluid source and the servomotor is again actuated to re-establish this fluid connection. The press ram, assuming that it has settled from its retracted

25 position, is then effective, through linkage, to shift the pump on retraction stroke and thereby return the press ram to its fully retracted position. In this manner, the prime mover is permitted to come up to speed under no load, thereby protecting the prime mover, reducing the length of time required for starting and substantially reducing the power requirements for starting.

30 The valve means provided in the pilot fluid circuit are further operable by manual means whereby to prevent the delivery of fluid from the main pump at any time. In response to the actuation of said manual means, the valve means in the pilot fluid circuit are actuated to exhaust the pressure fluid from the servomotor thereby permitting the previously mentioned centering

means rapidly to shift the pump to neutral or no delivery position. The pump is thus caused to cease delivering fluid suddenly and at the will of the operator and, in case a reciprocable hydraulic motor is being actuated by said fluid, the same will also suddenly stop and remain in position until the pump is again shifted on stroke. Other manual means are effective to counteract the effect of the first mentioned manual means, that is, to actuate the control valve in the pilot fluid circuit to again deliver pilot fluid to the servomotor. To this end, there is provided an electric circuit, including push buttons and valve actuating solenoids, for controlling the actuation of the valve means in the pilot fluid circuit.

According to another feature of this invention, the valve means controlling the supply of fluid from the auxiliary fluid source to the servomotor means is adapted, at a predetermined point of travel of the press ram, temporarily to interrupt or by-pass the fluid flow from said auxiliary source to said servomotor means to bring about a temporary slow-down of the press ram.

Structural arrangement

Referring now to the drawings in detail, and in particular to Figure 1, the structure disclosed therein comprises a press cylinder 1 having mounted reciprocably therein a press ram 2 which is connected to a press platen 3. The platen 3 carries an arm 4 which is adapted to engage the collar 5, adjustably mounted on a push rod 6, which rod is suitably reciprocably mounted and guided by any convenient guiding means such as the stationary bracket 7. Also adjustably mounted on the push rod 6 is a collar 8 which is adapted to engage the fixed bracket 7 and thereby limit the downward movement of the rod 6.

Furthermore, adjustably mounted on the push rod 6 is a collar 9 adapted to engage the arm 10 of a three arm lever, generally designated at 11. A second arm of the lever 11 is pivotally connected with a link 12, which, in turn, is connected to the armature 13 of a solenoid. This solenoid 14, which is the main operating solenoid, is so arranged in relation to the armature 13, that energization of the solenoid will cause the armature 13 to move downwardly, thereby rotating the lever 11 in a clock-wise direction about the pivot 15. The third arm of the lever 11 is connected through a suitable linkage system, generally indicated at 16, with the control rod of the pump servomotor.

The pump servomotor, generally indicated at 18, comprises a double acting piston 19 within which is reciprocable the valve member 20. In turn, the valve member 20 is connected with the control rod 17, this last mentioned member being reciprocable through a bore in the end cover of the servomotor. The servomotor 18 is suitably connected to a variable delivery pump 21 in any convenient manner. The pump 21 may be of any type as, for instance, a radial piston or a radial vane pump. The pump is preferably of the reversible type, that is, capable of delivery in both directions.

The servomotor piston 19 has a larger diameter portion 22 reciprocable within a bore 23 of the servomotor 18 and a smaller diameter portion 24 reciprocable within the bore 25 of the servomotor 18. The smaller diameter portion 24 is provided with a bore 26 which is in communication with the central bore 27 of the servomotor

piston and the longitudinal bore 28. A second radial bore at 29 is adapted to effect communication between the bore 27 and the bore 23. The valve member 20 fits within the bore 27 and is preferably of such a length as to exactly cover both of the radial bores 26 and 29 at one time. The valve member 20 is, therefore, adapted to uncover one of the bores 29 or 26 when it is moved from the position indicated in Figure 1.

10 A conduit 30 delivers pressure fluid into the servomotor 18 at the right hand end of the bore 23. A second conduit 31, which includes a check valve 32, is connected from the conduit 30 into the left hand end of the bore 23 whereby fluid may pass from the conduit 31 into the conduit 30 but not vice versa.

20 A conduit 33 is connected into the servomotor at the right hand end of the bore 25 and serves to conduct the exhaust fluid from the servomotor back to the reservoir or tank 34. Bores 35 are effective to establish communication between the portion of the bore 25, which is drained by the conduit 33, and the bore 27.

25 The servomotor piston 19 is connected by means of the extension 36 with the flow control member of the pump 21 and, therefore, when being moved is adapted to vary the rate and direction of delivery of fluid from said pump.

30 The valve member 20 is continuously urged, by means of a spring 37, towards its left hand position for a purpose which will hereinafter become apparent.

35 The pump 21 is further fitted with centering springs generally indicated at 38 which serve continuously to urge the pump towards no delivery position. A rod 39 is affixed to the flow control member of the pump 21 and has an enlarged diameter portion thereon at 40. A pair of collars 41, slideable on rod 39, are urged by the springs 42 towards the position shown in Figure 1. In this position the collars 41 engage a fixed annular ring 43 and thereby locate the rod 39 so as to hold the flow control member of the pump in no delivery position. The servomotor piston 19 is effective to move the flow control member of the pump against the thrust of one of the springs 42 to move the pump to forward or reverse delivery.

40 Pilot fluid is supplied to the pump servomotor by means of the pilot pump indicated at 44. The pump 44 draws fluid from the reservoir 34 through a conduit 45 and delivers the same at increased pressure through the conduit 46 to the four way valve 47 from where the pilot fluid is conducted through conduit 48 to a second four way valve 49. The valve 49 delivers the pilot fluid directly to the conduit 30 which is in continuous communication with the servomotor 18.

45 The valve 47 is provided with a spring 50 continuously urging the valve member into the position shown in Figure 1, and is further provided with a solenoid 51 which is adapted, upon energization, to move the valve member of the valve 47 to the right. Movement of the valve member to the right is effective to establish communication between conduit 48 and the exhaust conduit 52, and also to establish communication between the conduit 46 and the exhaust conduit 52, thereby by-passing the delivery of the pilot pump 44 and exhausting the servomotor 18.

50 The valve 49 is similarly provided with a spring 53 urging the movable valve member to the left, and with a solenoid 54 which is adapted, upon energization, to move said valve member to the right. Movement to the right of the valve member of the valve 49 is effective to establish fluid

communication between the conduit 30 and the conduit 55 and between the conduits 48 and 52. The conduit 55 includes an adjustable choke valve 58 whereby the rate of exhaust from the conduit 30 to the conduit 52, when the valve member within the valve 49 is shifted, may be controlled.

The pilot pump 44 is further provided with the pressure relief valve 57 through which the excess capacity of the pump 44 is discharged to exhaust when not being utilized in the operation of the servomotor or being by-passed through one of the valves 47, 49 to the tank. The pilot pump 44 may be driven from the shaft of the main pump 21 or by a separate motor as at 58.

The main pump 21 is driven by a suitable prime mover such as the electric motor indicated at 59, to which it is connected by suitable shafting possibly including a flexible coupling. The pump 21 is connected by means of a conduit 60 with the upper portion of the press cylinder 1, and by means of a conduit 61 with the lower portion of the press cylinder 1. Connected to the conduit 60 is a conduit leading to the tonnage control valve indicated at 62, the function of which is to open the electric circuit to the main solenoid upon the accomplishment of a predetermined pressure within the upper portion of the press cylinder 1. This valve may be of any standard design, for instance, of the type disclosed in the United States Patent No. 2,224,957.

Mounted in the top of the press cylinder and extending therein is a surge valve indicated by the numeral 63. This valve, likewise, may be of any standard design, for instance, of the type disclosed in the United States Patent No. 2,193,248, and is adapted, in response to the suction effect created in the upper portion of the press cylinder 1 by the downward movement of the press ram 2, to open so as to admit fluid from the tank 34 to the upper portion of the cylinder 1. When a predetermined pressure develops in the upper portion of the cylinder 1 the surge valve closes. Pilot line 64 connects from the surge valve to the conduit 61 and the surge valve is thereby adapted, in response to a predetermined pressure in the lower portion of the cylinder 1 to open and admit to the tank the fluid from the top of the press cylinder. A check valve 65 is connected to the conduit 64 and permits make-up fluid to be drawn from the tank by the pump during the working portion of the press stroke.

Referring now to Figure 2 wherein is illustrated the wiring diagram system of Figure 1, the electric power is supplied by two main supply lines indicated at L1 and L2. The line L1 has connected thereto the line 66 which is adapted to be electrically connected with the line 67 by closure of the line switch 68. The line 67 is connected through the normally closed stop switch 69 with the line 70 which in turn is connected to a line 71. Between the lines 71 and L2 the remainder of the electrical circuit is arranged in branch lines. The line 71 is adapted, upon closure of the normally open switch 72 to complete a circuit through the normally closed timer blades T1 and the relay coil R1 with the line L2. Energization of R1 causes the normally open blades R1A, R1B and R1C to close and the normally closed blades R1D to open. The closure of the blades R1A provides a holding circuit for the relay coil R1 which thus remains energized subsequent to the opening of the switch 72.

Closure of the blades R1B energizes the relay coil R2 and also energizes the winding of the motors 58 and 59 which are arranged in parallel

with the relay coil R2. The energization of the relay coil R2 is effective to close the normally open blades R2A and to thereby provide a holding circuit for the relay coil R2, the motor 58 and the motor 59. This circuit will be maintained until the switch 68 or the switch 69 is opened.

Arranged in parallel with the contactor coil R1, and energized simultaneously therewith, is 10 a timer indicated at T which is adapted, after the lapse of a predetermined time, to open the blades T1 momentarily and to thereby deenergize the contactor coil R1 and the timer. The deenergization of R1 permits the blades R1A, R1B and R1C to open while closing the blades R1D. The opening of the blades R1A serves to maintain the contactor coil R1 and the timer T deenergized until the switch 72 is again closed. The opening of the blades R1B has no effect on the circuit since the relay coil R2 is maintained energized through the blades R2A. The closing of the blades R1D conditions the circuit including the main solenoid 14 and the forward push button switch to be energized when said switch is closed.

25 The main solenoid 14 is connected between the lines L2 and 71 through the blades R1D and the normally open push button 73. The push button 73 is by-passed by a holding circuit which 30 includes the tonnage control switch 62A, a reversing push button 74 and a pair of normally open blades 14A. The blades 14A are adapted to be closed upon the energization of the main solenoid 14.

35 The solenoid 51 of the valve 47 is connected between the lines L2 and 71 through the switch blades R1C, the latter being by-passed by a circuit including the normally open blades R3A. The solenoid 51 is thereby adapted to be energized upon the closure of either the switch blades R1C or R3A.

40 The relay coil R3 is connected between the lines L2 and 71 through the normally open emergency stop push button 75, which latter switch is by-passed by the normally closed push button 76 and the normally open contactor blades R3B. The last mentioned circuit provides a holding circuit which is effective to maintain the coil R3 energized subsequent to the closing of the switch 50 75 and prior to the opening of the switch 76.

45 The solenoid 54 of the valve 49 is connected between lines L2 and 71 through the normally open limit switch 77. The switch 77 is adapted to be closed by the cam 78 carried on the platen 3 during the advancing stroke of said platen. Further advance of the platen beyond the point where the switch 77 is closed will permit the switch 77 to open, and to remain open, until the cam 78 again approaches the switch 77 from above during the forward travel of the press ram.

Operation

55 It may be assumed that all parts of the system occupy the position shown in Figure 1, with the exception of the ram 2, which may be assumed to be settled below its fully retracted position to occupy a position intermediate its end positions so that the rod 11 and the servomotor 70 valve 20 is moved to the left with regard to the position shown in Figure 1. It may further be assumed that the driving motors 58 and 59 are at a standstill.

If it is now desired to cause the press ram 2 75 to perform a working cycle, it is first necessary

to retract the ram to its uppermost or fully retracted position, that is, to the position shown in Figure 1. To this end, the operator closes the line switch 68 and then presses starter switch 72. As a result thereof, the energizing circuit for the contactor R1 and the timer T is closed. Energization of the contactor coil R1 closes the blades R1A and R1B thereby providing a holding circuit for R1 and energizing R2. Energization of coil R2 operates to close switch R2A, thus establishing a holding circuit for R2. Simultaneously, the blades R1D are opened thereby insuring that the main solenoid 14 is deenergized and will remain deenergized until the contactor coil R1 is again deenergized. Also simultaneously, the blades R1C are closed and energize the solenoid 51 of the valve 47. The valve 47 is thereby shifted to the right by-passing the pilot fluid from the pump 44 and exhausting the servomotor 18.

These conditions prevail until the timer T has run its predetermined period and opens the blades T1. Opening of the blades T1 deenergizes the contactor coil R1 and the timer T and the blades R1A, R1B and R1C are opened. The opening of the blades R1A is effective to maintain the coil R1 in the timer T deenergized until the switch 72 is again closed to start the press in operation. The opening of the blades R1B is not effective since the coil R2 is maintained energized by its holding circuit through the blades R2A. The motors 58 and 59 continue to be energized since they are in parallel with the coil R2.

The opening of the blades R1C, simultaneously with the opening of R1A and R1B, is effective to deenergize the solenoid 51 of the valve 47 thereby permitting the spring 50 to shift the valve member leftwardly to the position shown in Figure 1. The shifting of the valve member in the valve 47 by the spring 50 permits fluid from the pilot pump 44 to be conducted to the pump servomotor 18 where it is utilized in moving the pump to stroke against the thrust of the centering springs 42. Since it was assumed that the press ram 2 had settled downwardly from its retracted position, the linkage 16 would be positioned to shift the pump to retraction stroke and fluid would thereby be delivered through the conduit 61 to the retraction area of the hydraulic motor, and the press ram would move to the position shown in Figure 1.

The period of time during which the timer is energized, that is, subsequent to the closing of the switch 72 and prior to the opening of the blades T1, is sufficient to permit the motors 58 and 59 to come up to full speed. The driving motor or motors are, therefore, started under no load and auxiliary starting equipment is not necessary.

If it is now desired to initiate a working cycle of the press, the operator presses the forward push button 73 thereby energizing the main solenoid 14 and shifting the linkage 16 to put the pump on forward stroke. Energization of solenoid 14 operates to close switch 14A and thus establish a holding circuit for solenoid 14 through tonnage switch 62 and reversing switch 74. The action of the servomotor at this time is as follows:

The valve member 20 is shifted to the right by the rod 17 against the thrust of the spring 37 and uncovers the inner end of the radial passage 29. Pilot fluid entering the right end of the bore 23 through the conduit 30 is thereby permitted to flow through the passage 29 and 70

the bore 27 into the left end of the bore 23. The area of the servomotor piston 19 which is exposed to the fluid in the left hand side of the chamber 23 is larger than the area of the piston 19 which is exposed to the pressure fluid in the right hand end of the bore 23. The piston 19 is, therefore, urged to the right and will move rightwardly until the passage 29 is once more blocked by the valve member 20.

The pump now delivers fluid into the conduit 60 and draws fluid in from the conduit 61. The fluid drawn into the conduit 61 is removed from the retraction area of the hydraulic motor and the ram 2 moves downwardly as rapidly as this fluid is withdrawn. During this part of the forward stroke the suction created above the ram 2 is effective to open the surge valve 63 thereby permitting fluid to enter the chamber above the ram 2 from the tank. After the platen has engaged the work the surge valve 63 closes and the fluid delivered by the pump into conduit 60 is effective to create pressure above the ram 2. During this part of the stroke the pump draws fluid through conduit 61 from the retraction area of the hydraulic motor and also through the conduit 64 and the check valve 65 from the tank 34.

Upon the accomplishment of a predetermined pressure within the main cylinder 1 the tonnage control valve 62 is actuated to open the holding circuit of the main solenoid 14 and the reversal of the press now takes place. Optionally, the holding circuit of the solenoid 14 may be operated by a limit switch (not shown) or by the reverse push button 14. In any event, deenergization of the solenoid 14 is effective to permit the spring 37 to move the valve member 20 to the left. The left end of the bore 23 is now opened to the exhaust conduit 33 through the bore 28, the bore 26, the bore 27 and the bores 35. The pressure prevailing in the right end of the bore 23 is, therefore, effective to move the servomotor piston 19 to the left to follow the movement of the valve member 20. The movement leftwardly of the piston 19 is effective to shift the pump 21 to retraction stroke and fluid is now withdrawn from conduit 60 and driven through conduit 61 to the retraction area of the hydraulic motor. During the retraction stroke the pressure in the conduit 61 is conveyed through conduit 64 to the surge valve 63 and is effective to maintain that valve in an open position thereby permitting the fluid above the ram 2 within the cylinder 1 to be expelled into the tank 34. The platen moves upwardly until the control rod 6 is actuated by the arm 4 and the collar 5 to move the linkage 16 to the position shown in Figure 1 when the platen comes to a rest.

If the switch 77 is adapted to be engaged by the cam 18 during the downward stroke of the press, a slow down of the forward travel of the press ram is accomplished as follows:

Closure of the switch 77 energizes the solenoid 54 of the valve 49 thereby shifting the valve member of the valve 49 to the right. Movement to the right of this member interconnects the conduit 48 and the conduit 52 thereby by-passing the delivery of the pilot pump to exhaust, and also interconnects the conduits 30 and 55 thereby exhausting the servomotor through the choke valve 56 to conduit 52 and exhaust. The release of pilot fluid from the servomotor 18 permits the centering springs 42 to move the pump towards neutral or no delivery position. The fluid expelled from the servomotor passes through the conduit 30 to

the conduit 55 and thence through the choke valve 56 to the conduit 52, and the rate at which the fluid flows therethrough is governed by the setting of the choke 56. The choke 56 is so adjusted that before the pump reaches center or no delivery position the platen has passed beyond the switch 77 and has permitted the latter to open. The opening of the switch 77 is effective to de-energize the solenoid 54 thereby permitting the spring 53 to shift the valve member of the valve 49 to the left to the position shown in Figure 1 thereby re-establishing fluid connection between the pilot pump and the servomotor. Immediately upon the reestablishment of the pilot fluid circuit to the servomotor the pump is shifted on to stroke and the downward movement of the press ram and platen is continued. In this manner it is possible to check the rapid advance of the platen just before it engages the work whereby the shock of contact is materially reduced. The switch 77 is adapted to be effective on the downward stroke of the press ram but is ineffective on the upward stroke and thus causes no delay during the retraction stroke.

If, at any time during the retraction or forward strokes, it is desired or necessary to bring the press ram to a sudden halt, the operator depresses the emergency stop switch 75. The closing of the switch 75 energizes the contactor coil R3 which in turn closes the blades R3A and R3B. The blades R3A are effective, when closed, to complete a circuit between the lines 71 and L2 through the solenoid 51 of the valve 47. Energization of the solenoid 51 shifts the valve member of the valve 47 to the right interconnecting the conduits 46 and 52 thus by-passing the delivery of the pilot pump to exhaust and also interconnects the conduits 48 and 52 thereby exhausting the servomotor 18. With the servomotor connected to exhaust the centering springs 42 are effective rapidly to shift the pump 21 to neutral or zero delivery position. The conduit 31 and check valve 32 are effective at this time to permit rapid evacuation of the left hand end of the bore 23 should the servomotor piston be shifted from forward toward neutral.

With the pump shifted to and held in neutral by the springs 42, there is no delivery into either of the conduits 60 or 61 and, therefore, any equipment, such as the press ram 2, being actuated by fluid from one of the conduits will cease to operate and come to a halt. Therefore, in the device illustrated, the switch 75 is effective to halt the press ram 2 at any point during the forward or reverse strokes.

The pump having been shifted to neutral by the closing of the switch 75, will remain so until the switch 76 is depressed to deenergize the coil R3. When the switch 76 is opened to deenergize the coil R3, the blades R3A and R3B will open, the valve solenoid 51 will be deenergized, and the holding circuit of the coil R3 will be opened. Deenergization of the solenoid 51 permits the spring 50 to shift the valve member within the valve 47 to the position shown in Figure 1 and fluid connection between the pilot pump 34 and the servomotor 18 is again established. As before, establishment of the pilot fluid circuit permits the servomotor piston 19 to place the pump on stroke, according to the position occupied by the valve member 20. The switch 75 is, therefore, effective upon operation to suddenly and effectively bring the pump 21 to a neutral position and to thereby halt the flow of fluid through the associated hydraulic circuit, and the switch 76

is effective, upon operation, to counteract the influence of the switch 75 thus restoring the original condition in the entire system.

It will be appreciated that the method just described for centering the pump 21 and halting the ram 2 is more effective than would be the opening of the switches 68 or 69, inasmuch as the opening of either of the last mentioned switches is effective to halt the pump delivery or to stop the ram 2 only after the pumps and motors have coasted to a stop. Because of the inertia of these members, a considerable period of time would transpire between the opening of either of the switches 68 or 69 and the halting of the press ram 2 or the cessation of delivery by the pump 21.

If desired, the pilot pump 48 may be replaced by an accumulator or other suitable source of pressure, in which case certain simplifications in the hydraulic and electric circuit could be effected. It will be understood, however, that the operation of this invention would not be effected by the replacement of the pilot pump 44 by the equivalent accumulator.

It will be understood that I do not desire to be limited by the particular structure and arrangement indicated in the drawings but desire to comprehend such modifications as may come within the scope of the claims.

Having thus fully described my invention, what I claim as new and desire to secure by Letters Patents is:

1. A hydraulic actuating system that includes a variable delivery pump, a prime mover for driving said pump, first means operable automatically by and upon energization of said prime mover to position said pump in neutral prior to said prime mover reaching a predetermined speed, and control means selectively operable at any time for actuating said first means to position said pump in neutral.

2. A hydraulic actuating system that includes a fluid source of variable delivery, fluid operable flow control means for controlling the delivery of said fluid source, means supplying actuating fluid to said control means, a prime mover for actuating said source, first, means operable automatically by and upon energization of said prime mover for preventing the supply of actuating fluid to said fluid operated control means prior to said prime mover reaching a predetermined speed and means selectively operable at any time for actuating said first means to prevent the supply of actuating fluid to said fluid operable flow control means.

55 3. A hydraulic actuating system including a variable delivery pump, an electric motor connected to drive said pump, pressure operable servomotor means for varying the delivery of said pump, yielding means connected to continuously urge said pump toward no-delivery position, means automatically operable by and upon energization of said prime mover to prevent the supply of actuating pressure fluid to said servomotor while said electric motor is accelerating to a predetermined minimum speed, and manual means operable at will to actuate said automatically operable means.

4. A hydraulic actuating system including a reversible variable delivery pump, a prime mover connected to drive said pump, a fluid operable servomotor connected to vary the delivery of said pump, centering means associated with said pump and continuously urging said pump toward no delivery position, an auxiliary fluid source for supplying actuating fluid to said servomotor, means

automatically operable by and upon energization of said prime mover, to prevent the supply of fluid from said auxiliary source to said servomotor and to exhaust said servomotor, and manual means operable at will to actuate said automatically operable means and thus prevent the supply of fluid from said auxiliary source to said servomotor.

5. In a hydraulic system, a variable delivery pump, means yieldingly urging said pump into neutral, fluid pressure operated servomotor means connected to vary the delivery of said pump against the action of said yielding means, a source of pressure fluid for said servomotor, a prime mover connected to drive said pump, connections between said source, said servomotor, and exhaust, first valve means in said connections, operable to connect said servomotor to exhaust; means operated by and for a limited time after energization of said prime mover to operate said first valve means, and second valve means in said connections operable at will to exhaust said servomotor means at a predetermined desired rate.

6. A hydraulic actuating system that includes a variable delivery pump, an electric motor for driving said pump, a fluid operable servomotor for varying the delivery of said pump, centering means continuously urging said pump into and tending to hold the same in substantially neutral or no delivery position, means automatically operable to prevent the supply of actuating fluid to said fluid operable servomotor prior to said electric motor attaining a predetermined speed, manual means operable selectively to prevent the supply of actuating fluid to said servomotor while simultaneously exhausting said servomotor and other means to prevent the supply of actuating fluid to said servomotor while controllably exhausting said servomotor.

7. A hydraulic actuating system that includes a variable delivery pump, fluid operable flow control means for varying the delivery of said pump, centering means continuously urging said pump towards neutral or no delivery position, an electric motor having a driving shaft connected with the driving shaft of said pump, an auxiliary fluid source for supplying actuating fluid to said fluid operable flow control means, means automatically operable in response to the energization of said electric motor to prevent the supply of fluid from said auxiliary source to said flow control means prior to said motor attaining a predetermined minimum speed, a first means selectively operable to interrupt fluid communication between said auxiliary source and said flow control means while freely exhausting the latter, a second means operable to counteract said first means and thereby to restore fluid communication between said auxiliary source and said flow control means, and other means selectively operable to interrupt fluid communication between said auxiliary source and said flow control means while partially exhausting said servomotor whereby to permit said centering means to reduce the delivery of said pump.

8. A hydraulic actuating system that includes a variable delivery pump, a fluid operable servomotor for varying the delivery of said pump, centering means continuously urging said pump into and tending to hold the same in substantially neutral or no delivery position, an electric motor drivingly connected with said pump, a pilot pump for supplying actuating fluid to said servomotor, control means for controlling the supply of fluid from said pilot pump to said servomotor, means

operable in response to the starting of said electric motor for actuating said control means for preventing the supply of fluid from said pilot pump to said servomotor prior to said electric motor attaining a predetermined minimum speed, manual means selectively operable to actuate said control means to interrupt fluid communication between said pilot pump and said servomotor while freely exhausting said servomotor whereby to permit said centering means to move said pump to no delivery position, other manual means operable to counteract said first mentioned manual means whereby to actuate said control means to restore fluid communication between said pilot pump and said servomotor whereby to move said pump into delivery position, automatic means operable to actuate said control means to interrupt fluid communication between said pilot pump and said servomotor while partially exhausting said servomotor whereby to permit said centering means to bring about a reduction in the delivery of said pump, and means for counteracting said last mentioned means whereby to restore fluid communication between said pilot pump and said servomotor.

9. A hydraulic actuating system that includes a fluid operable reciprocating plunger, a variable delivery pump for supplying pressure fluid to said plunger for actuating the same, yielding means continuously urging said pump toward substantially neutral or no delivery position, fluid operable servomotor means for moving said pump on to stroke against the thrust of said yielding means, a prime mover drivingly connected to said pump, an auxiliary source of pressure fluid for actuating said servomotor, valve means for controlling the supply of fluid from said auxiliary source to said servomotor, means responsive to the initiation of the starting of said prime mover for actuating said valve means to prevent the supply of fluid from said auxiliary source to said servomotor while exhausting said servomotor, said means being effective over a predetermined period of time, manual means selectively operable to actuate said valve means to interrupt the supply of fluid from said auxiliary source to said servomotor while exhausting said servomotor, and means operable in response to a predetermined position of said plunger for actuating said valve means to prevent the supply of fluid from said auxiliary source to said servomotor while exhausting said servomotor and means associated with said last mentioned means for controlling the rate of exhaust from said servomotor.

10. In a hydraulic system, hydraulic motor means, a variable delivery pump, yielding means urging said pump into substantially no delivery position, fluid operable servomotor means for moving said pump into delivery position against the thrust of said yielding means, pilot fluid supply means for supplying actuating fluid to said servomotor means, an electric motor having its driving shaft connected to the rotor of said pump, a first valve means for controlling the supply of fluid from said pilot fluid supply means to said servomotor means and operable to prevent the supply of fluid from said pilot fluid supply means to said servomotor while permitting said servomotor to be freely exhausted, a second valve means for controlling the supply of fluid from said pilot fluid supply means to said servomotor means and operable to prevent the supply of fluid from said pilot fluid supply means to said servomotor means while controllably exhausting said servomotor, means operable in response to the

initiation of the starting of said electric motor to actuate said first valve means prior to said electric motor attaining a predetermined minimum speed, manual means selectively operable to actuate said first valve means, and means responsive to a predetermined movement of said hydraulic motor means for actuating said second valve means.

11. In a hydraulic system, a fluid operable reciprocable plunger, a variable delivery pump for supplying actuating fluid to said plunger, yielding means continuously urging said pump into substantially no delivery position, fluid operable servomotor means for selectively moving said pump into delivery position against the thrust of said yielding means, pilot fluid supply means for supplying actuating fluid to said servomotor means, an electric motor drivingly connected to said pump, a first means for bypassing the delivery of said pilot fluid supply means while simultaneously and freely exhausting said servomotor means, a second means for bypassing the delivery of said pilot fluid supply means while simultaneously and controllably exhausting said servomotor means, means associated with the starting circuit of said electric motor and operable in response to the energization thereof for actuating said first means for a predetermined period of time, manual means selectively operable to actuate said first mentioned means, other manual means operable to counteract said last mentioned manual means, means responsive to a predetermined position of forward travel of said plunger for actuating said second means, and means responsive to the continued advance of said plunger for counteracting said last mentioned means.

12. In a hydraulic actuating system, a variable delivery pump, pressure operated means connected to vary the delivery of said pump, power means connected to drive said pump, a source of pressure, conduit means between said source and said pressure operated means and including a valve having an exhaust outlet, and means operated for a predetermined time only by and after energization of said power means, to actuate said valve, thereby to close said conduit means and connect said pressure operated means to exhaust.

13. In a hydraulic system, a variable delivery pump, pressure-actuated control means connected to vary the delivery of said pump, power means connected to drive said pump, a source of auxiliary fluid under pressure, conduit means between said source and control means and including normally open first and second valves connected in series, said first valve being freely connected to exhaust, means operated by and upon energization of said power means to actuate said first valve to connect said source and said control means to exhaust, said second valve being connected to exhaust through choke means, and means operable at will to operate said second valve to exhaust said control means through said choke means.

14. In combination with a pump having pressure-operated control means for varying the delivery thereof, power means connected to drive said pump, a source of pressure fluid, a connection from said source to said control means, a valve in said connection having an exhaust connection, means operated by and for a predetermined time after start of said power means to actuate said valve and thereby connect said control means to exhaust, second valve means in said connection operable at will to exhaust said control means at a predetermined reduced rate, and means yieldingly urging said pump into neutral against the operation of said control means.
